UNITED STATES PATENT OFFICE.

WILLIAM J. SEUFERT, OF THE DALLES, OREGON.

CARBURETER.

Specification of Letters Patent. Patented Mar. 16, 1920.

1,334,263.

Application filed June 7, 1918. Serial No. 238,708.

To all whom it may concern:

Be it known that I, WILLIAM J. SEUFERT, a citizen of the United States, residing at The Dalles, in the county of Wasco and State of Oregon, have invented new and useful Improvements in Carbureters, of which the following is a specification.

This invention relates to new and useful improvements in carbureters and the principal object of the invention is to provide means for securing a combustible mixture from low grade gasoline for operating torches and the like.

Another object of the invention is to provide a device in which the hydrocarbon fuel under the action of gravity passes slowly through an air current and having means for collecting the liquid not carried off by the air current and passing it through the current again.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an end elevation of the invention.

Fig. 2 is a front elevation.

Fig. 3 is a longitudinal section.

Fig. 4 is a transverse section on line 4—4 of Fig. 3.

Fig. 5 is a section on line 5—5 of Fig. 3.

As shown in these views the invention comprises a cylindrical casing 1 having journals 2 projecting from its front and rear faces, said journals being of tubular form. These journals are supported by the uprights 3, each of which is provided with a passage way 4 communicating with said journals, and said uprights are secured to a suitable base 5.

6 indicates a nut located in the right angular end of each upright and surround-

ing the journal. These nuts form parts of packing glands as shown. The passage way 4 is the gas outlet which leads to a suitable storage receptacle or directly to the burner while the passage way 4' is the air inlet which is connected with a suitable air pump or other source of air supply.

7 and 8 indicate the gasoline compartments located at opposite ends of the casing. One of these compartments is provided with a filling plug 9 through which the gasoline is poured into the device. Each compartment is also provided with an inlet tube 10 extending from the inner part of the compartment to a point adjacent the end of the casing so that the gasoline will not flow into said tube when the compartment is in its upper position, but will flow therethrough from the interior of the casing when the compartment is in its lower position. Spaced from the inner end of each gasoline compartment is a perforated plate 11, which is provided with projections 12 and 13, which project on each side of the plate and are perforated to permit the gasoline to flow therethrough. These projections form depressions on the opposite sides of the plate, as shown.

The plates 11 form the ends of a large central compartment 14 centrally arranged in the casing and this compartment is divided longitudinally into an enlarged central part and two outer parts 15 and 16 by the perforated plates 17 which are arranged at right angles to the plates 11 and have their ends connected to said plates. The part 15 of said compartment communicates with the air inlet while the part 16 communicates with the gas outlet so that the incoming air strikes the first plate and is distributed over the same and passes through the perforations therein to the central part of the large compartment 14, and then passes through the perforations in the other plate 17 into the part 16 and out through the gas outlet. As the air passes through the central part of the compartment it is brought into contact with the gasoline dropping from the upper plate 11 on to the lower plate. The gasoline is fed from the gasoline compartment on to said plate by means of a sight feed and connecting tubes hereinafter described.

I prefer to provide strips 18 of wire gauze or wicking in said central compartment, which have their ends connected with the plates 11, preferably at a point adjacent the

perforations therein so that the gasoline passing through said perforations will be taken up by said strips and will slowly pass down the same to the lower plate 11. In 5 this way the air current will take up the maximum amount of gas or vapor. The remaining liquid will flow into the depressions formed by the projections 12 on the lower plate and drop through the perforations 10 therein on to the inner part of the lower gasoline compartment 8 and will flow into the tube 10 and thus enter the said compartment.

Each gasoline compartment is provided 15 with an air vent tube 19 of looped form and having its inner end located at a point adjacent the inner wall of the compartment and its other end passing through said inner wall so that the air can escape from the top of 20 the lower compartment. Each gasoline compartment is provided with a sight feed 20 controlled by a valve 21, said sight feed being located on the front face of the casing and connected with the gasoline compartment 25 by a suitable tube and strainer 20'. The outlet end of the sight feed is connected with a distributing tube 22 located adjacent the plate 11 for distributing the gasoline on to said plate. The rear face of the casing 30 is provided with a pair of enlargements 23 located at diametrically opposite points and each enlargement is provided with a depression 24.

A spring controlled catch member 25 carried by a standard 26 secured to the upper end of one of the uprights 3, is adapted to engage with one of the depressions for holding one of the gasoline compartments in its uppermost position. When one of the gasoline compartments is empty, which may 40 readily be seen from the sight feed, the catch member is retracted and the casing reversed to place the full compartment in its uppermost position so that the gasoline will 45 be caused to flow through the device in an opposite direction.

It is thought from the foregoing description that the advantages and novel features of my invention will be readily apparent.

50 I desire it to be understood that I may make such changes in the construction and in the combination and arrangement of the

several parts, provided that such changes fall within the scope of the appended claims.

What I claim is:—

55 1. A carbureting device comprising a casing having therein a central mixing chamber and a fuel chamber at each end thereof, means for passing a current of air through said mixing chamber, means for feeding the fuel from one fuel chamber, means for directing the unvaporized fuel into the second fuel chamber and means for reversing the casing to cause the fuel to be fed in the reverse direction.

65 2. A carbureting device comprising a casing, having therein a pair of fuel chambers and a mixing chamber between them, means for passing a current of air through said mixing chamber, a perforated plate located 70 at each end of the mixing chamber and adjacent the fuel chamber, means for feeding the fuel from the fuel chamber on to said plates and means carried by said plates for collecting the unvaporized fuel fed from one 75 fuel chamber and directing it into the other chamber.

3. A carbureting device comprising a casing having a fuel chamber at each end thereof and a mixing chamber between said 80 fuel chamber, a perforated plate located adjacent each end of the mixing chamber, means for feeding the fuel from said fuel chambers on to said plates, strips extending between the perforated plates, means for 85 passing a current of air through said mixing chamber and means for reversing the casing.

4. A carbureting device comprising a casing having therein a pair of fuel chambers and a mixing chamber, said mixing chamber being located between the fuel chambers, means for passing a current of air through said mixing chamber, sight feed 90 means for feeding the fuel from the fuel chambers to the mixing chamber, an inward 95 tube in each fuel chamber, said tube passing through the inner wall of the chamber and extending at a point adjacent the outer wall thereof and a vent tube of substantially U-shape connected with each mixing chamber.

In testimony whereof I affix my signature.

WILLIAM J. SEUFERT.
